Primary Examiner — Mary Ann Calabrese*Assistant Examiner* — Catherine Ho(74) *Attorney, Agent, or Firm* — Banner & Witcoff, Ltd.(57) **CLAIM**

The ornamental design for a label, as shown and described.

DESCRIPTION

FIG. 1 is a front isometric view of a label showing our new design; and,

FIG. 2 is a front view thereof.

The broken lines representing alphanumeric content represents illustrative content which forms no part of the claimed design. The two broken line rectangles represent unclaimed regions and form no part of the claimed design. The broken lines showing the thickness of the label represent unclaimed subject matter and form no part of the claimed design.
